LIGHTING APPARATUS

Paul H. Irmischer, Chicago, Ill.

Application August 28, 1944, Serial No. 551,490

7 Claims. (Cl. 200—51)

1

This invention relates to new and useful improvements in lighting apparatus and has particular relation to the lighting systems employing fluorescent lamps.

More specifically my invention has to do with the lamp conductor means and control switches therefor. Viewed from this aspect an object of the invention is the provision of an arrangement of parts for supporting the lamp and controlling the energization thereof by mechanism that is simple in construction and arrangement, comprising few parts affording expeditious assembly resulting in economical manufacturing cost.

In the operation of fluorescent lamps now in general use it is the required practice to have the current heat up the filaments of the lamp and vaporize the mercury therein so that thereafter the current flow is through the lamp vapor and the lamp thus lighted. To extinguish the lamp a push button is momentarily depressed to open the lamp circuit with the results that the vapor in the lamp condenses and the lamp extinguished.

This present invention has particular reference to the relation of these control switches with respect to means serving the dual purpose of conducting current to the lamp and as a mounting therefor resulting in an apparatus which is simple in construction and design.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is a perspective view of the lighting apparatus embodying my invention;

Fig. 2 is a longitudinal sectional detail view of the same;

Fig. 3 is a sectional detail view taken substantially on line 3—3 of Fig. 1;

Fig. 4 is a sectional detail view taken substantially on line 4—4 of Fig. 2;

Fig. 5 is a perspective view of one of the conductors embodied in the invention;

Fig. 6 is a perspective view of another of the conductors embodied in the invention;

Fig. 7 is a sectional detail view taken substantially on line 7—7 of Fig. 3.

The several objects and advantages of my invention will become obvious from a consideration of the following detailed description taken in connection with the accompanying drawings wherein a fluorescent lamp is indicated at 10. This lamp comprises at each end electrodes or

2

terminals 11 and 11' which have connection in the usual and standard way with the filaments of the lamp.

A mounting for this lamp 10 is indicated at 12 and this mounting includes a base 13 from which extend end panels 14. This base comprises two sections 15 and 16 connected together by screws 17 located at suitable points with respect to the base. The top section 15 provides two parallel channels 17 and 18 spaced from each other by a rib 19. These channels at opposite ends thereof terminate into vertically extending openings 20 in turn terminating at their upper ends into slots 21 through which the ends of the electrodes 11 and 11' are projected for connection with conductor arms hereinafter described.

Formed in the bottom section 16 are longitudinally extending grooves 22 which receive the ribs 23 provided by the top section 15 to properly fit the sections 15 and 16 in conductor enclosing relation with respect to each other.

In the channel 17 is arranged a conductor 26' for the electrodes 11'. This conductor 26' comprises a bar 26 having at one end an angled finger 27 bifurcated as at 28 to receive the adjacent electrode of the electrodes 11'. The opposite end 29' of this bar has overlapping contact with a conductor strip 29 connected as at 30 to one side 31 of a source of electrical energy. Engaging this end 29' of the bar 26 is a push button 32, for reasons hereinafter set forth. The other side 33 of the source of electrical energy is connected as at 34 to a conductor strip 35 arranged in the channel 17' and having an angled end portion 27' similar to the finger 27 and arranged in the adjacent passage of the passages 20 and adapted to have contact with one of the electrodes 11.

In the channel 18 is arranged a conductor 36 comprising two bars 36' and 37 and each having angled end portions 38' providing fingers 38 similar to the finger 27 and each arranged in adjacent passage of the passages 20 for supporting connection with the other electrodes 11 and 11' of the lamp 10.

These bars 36' and 37 have overlapping portions 39' normally spaced from each other and adapted to be brought into contact with each other by a push button 39.

The conductors 26' and 36 are arranged in their respective channels 17' and 18 in the manner hereinbefore set forth and as shown in the drawings. When thus arranged it will be seen that they are completely enclosed and in condition to receive the lamp 10.

To energize the lamp, the push button 39 is

held depressed for a period sufficient to have the current heat up the filaments of the lamp and vaporize the mercury or gases in the lamp. The mercury or other gases now being vaporized in the lamp, the current flow is through the lamp vapor and the lamp is lighted. To extinguish the lamp the push button 32 is momentarily depressed to open the lamp circuit at which time the vapor in the lamp condenses and the lamp extinguished.

The energizing and extinguishing of the lamp in the manner explained is old in the art but in thus energizing and extinguishing the lamp prior to my invention, there were employed complicated switch structures and wiring arrangements. My lighting apparatus employs a very simple arrangement for this purpose. As is apparent from the description herein, I employ the conductors for the three-fold purpose of (1) supporting the lamp, (2) as conductor means, and (3) as switch means for energizing and extinguishing the lamp, thus dispensing with the conventional complicated switch and wiring arrangement with the result that a lamp is provided which will be highly efficient in use and economical in manufacture and free from the usual faulty conductor wires.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to protect by Letters Patent is:

1. A mounting for a lamp of the fluorescent type comprising conductors having means for supporting the lamp, one of said conductors comprising sections having overlapping ends normally spaced from each other, and the other of the conductors comprising spaced sections adapted for connection with a source of electrical energy and one of said spaced sections including parts having overlapping ends normally in contact with each other, means for separating said normally contacting overlapping ends, and means for moving said normally spaced ends together.

2. A mounting for a lamp of the fluorescent type comprising conductors in the form of elongated bars having means for supporting the lamp, one of said conductors comprising sections having overlapping ends normally spaced from each other and the other of the conductors comprising spaced sections adapted for connection with a source of electrical energy and one of said spaced sections including parts having overlapping ends normally in contact with each other, means for separating said normally contacting overlapping ends, and means for moving said normally spaced ends together.

3. A mounting for a lamp of the fluorescent type comprising conductors in the form of elongated bars having angled end portions, means for supporting the lamp, one of said conductors comprising sections having overlapping ends normally spaced from each other, and the other of the conductors comprising spaced sections adapted for connection with a source of electrical energy and one of said spaced sections including

parts having overlapping ends normally in contact with each other, means for separating said normally contacting overlapping ends, and means for moving said normally spaced ends together.

4. A mounting for a lamp of the fluorescent type comprising conductors having means for supporting the lamp, one of said conductors comprising sections having overlapping ends normally spaced from each other, and the other of the conductors comprising spaced sections adapted for connection with a source of electrical energy and one of said spaced sections including parts having overlapping ends normally in contact with each other, means for separating said normally contacting overlapping ends, means for moving said normally spaced ends together, and an enclosure for said conductors having means for spacing said conductors from each other.

20 5. A mounting for a lamp of the fluorescent type comprising conductors in the form of elongated bars having means for supporting the lamp, one of said conductors comprising sections having overlapping ends normally spaced from each other and the other of the conductors comprising spaced sections adapted for connection with a source of electrical energy and one of said spaced sections including parts having overlapping ends normally in contact with each other, means for separating said normally contacting overlapping ends, means for moving said normally spaced ends together, and an enclosure for said conductor bars having spaced grooves into which said conductor bars are mounted.

35 6. A mounting for a lamp of the fluorescent type comprising a base provided with spaced parallel grooves and end panels each having spaced parallel passages communicating with the grooves, conductors comprising elongated bars arranged in the grooves and having angled end portions positioned in the passages and adapted to support the lamp between the end panels, one of said conductors comprising sections having overlapping ends normally spaced from each other; and the other of the conductors comprising spaced sections adapted for connection with a source of electrical energy and one of said spaced sections including parts having overlapping ends normally in contact with each other, means for separating said normally contacting overlapping ends, and means for moving said normally spaced ends together.

40 7. A mounting for a lamp of the fluorescent type comprising a base including a top and bottom section together with means for detachably connecting said sections together and provided with spaced parallel grooves and end panels each having spaced parallel passages communicating with the grooves, conductors comprising elongated bars arranged in the grooves and having angled end portions positioned in the passages and adapted to support the lamp between the end panels, one of said conductors comprising sections having overlapping ends normally spaced

45 from each other, and the other of the conductors comprising spaced sections adapted for connection with a source of electrical energy and one of said spaced sections including parts having overlapping ends normally in contact with each other, means for separating said normally contacting overlapping ends, and means for moving said normally spaced ends together.

50 70 PAUL H. IRMISCHER.
